UNITED STATES PATENT OFFICE.

LUTHER C. McNEAL, OF ROCHESTER, NEW YORK.

MOP-WRINGER.

No. 868,799.

Specification of Letters Patent.

Patented Oct. 22, 1907.

Application filed July 9, 1906. Serial No. 325,203.

To all whom it may concern:

Be it known that I, LUTHER C. McNEAL, a citizen of the United States, and a resident of Rochester, in the county of Monroe and State of New York, have invented certain new and useful Improvements in Mop-Wringers, of which the following is a specification.

This invention relates to mop wringers of the class adapted to be removably attached to the side of a pail, and has for its object the production of a device that is 10 of simple construction, of great strength and efficiency and is rapid in operation when used to express the surplus water from the mop or any saturated fabric.

In the drawings:—Figure 1 is a vertical cross section on the line 1, 1 of Fig. 3, with the operating lever 15 raised to nearly a vertical position; Fig. 2 is a fragmentary view showing a modification of the movable presser in cross section; Fig. 3 is a rear elevation of the wringer; and Fig. 4 is a side elevation of the same.

Similar numerals refer to similar parts in all the 20 views.

The wringer, broadly speaking, comprises a frame supporting a stationary presser, a co-operating movable presser, means for attaching the wringer to a pail and means for operating and adjusting the movable presser.

25 The side frames 1 and 2 of the wringer are of the form shown in Figs. 1 and 4, and are preferably made of metal. A stationary presser-board 3, supported between lugs or flanges 3^a on the frames, separates the sides, and the latter are held in place by transverse 30 bolts 4. Openings or slots 5 in the sides 1 and 2 are adapted to fit over the edge of a pail, as shown in Fig. 1. Tongues 6, bearing against the outside of the pail, and the ends 7 touching the inside, hold the wringer securely in place.

35 In the upper part of each side-plate is a horizontal slot 8. The operating-shaft 9 extends through both of said slots, having a sliding fit therein. Holes 10, in line with the slots 8, form bearings for another shaft 11, parallel to the operating shaft.

40 The movable presser, as illustrated in Fig. 1, is supported between two channeled bars 12, and comprises two perforated plates 13 and 14. Brackets 15 on said bars support the bottom piece 16, which is usually of wood, as are also the presser-plates 13 and 14. A trans- 45 verse rod or bolt 17, connecting the lower ends of the side plates 1 and 2, forms a pivot for the bars 12. The operating means for moving the presser-plate is attached to ears or lugs 18 on the rear of said bars. The upper supplemental part 13 of the presser-plate is piv- 50 oted on pins 19 near its lower edge, said pins bearing in the side-bars 12. The said lower edge of this supplemental part is but a trifle above the upper edge of the plate 14, and so disposed that on the forward move- 55 ment of the plate 13 the lower edge will be engaged by the upper edge of the plate 14, and held thereby from further forward movement. A curved spring 20 bears

against the rear of the supplemental plate 13 and is held in place by studs 22 screwed into the bars 12 through slots 21 in said spring. The upper edge of the spring pressed member 13 projects inwardly beyond the inner face of the member 14 so that when the movable presser is moved toward the fixed presser 3 its upper spring pressed part 13 will begin to squeeze the mop at its top just in advance of the action by the member 14. This prevents the water from being thrown upward and also makes provision for inequalities in the mop being squeezed.

In Fig. 2 is shown a modified form of the movable presser. In this case the side bars are made in two sections 24 and 26, which are pivoted together at 23. 70 A presser plate 25 is supported between the two upper sections. This plate is normally held back by a leaf spring 27, which is screwed at 28 to the bottom plate 29, and is bent upward against said plate. Another flat spring 27^a secured to the lower section 26 bears 75 against the other side of said presser-plate, in a direction contrary to the spring 27. The presser-plate 25 is thus yieldingly held in an upright position, in alignment with the lower section 26. Ears or lugs 18^a project from the rear of the bars 24, and a spring 40 is 80 slipped over each. The pivot at the end of each operating link 32^a slides in a slot 40^a in said ears, and the spring 40 acts as a cushion between said link and the presser-plate 25, to prevent breakage of the latter.

The operating mechanism, or means for moving the 85 presser-plate, is actuated by the movement of the hand-lever 30, which is fixed in a casing 39 at one end of the shaft 9. Near each end of said shaft is fixed a pair of oppositely-disposed cranks, one of each pair being between the side frames 1 and 2, and the other of each 90 pair being just outside the said frames. (Figs. 1 and 4.) Links 32 pivoted at 44 connect the inner pair of cranks 31 with the ears or lugs 18, and similar links 36 and 37 pivoted at 45 connect the outside cranks 34 and 35 with pins 38, which project outwardly from the ends of the 95 shaft 11. When the lever 30 is depressed toward the stationary plate 3, the shaft 9 turns in the slot 8, and the cranks 31, 34 and 35, and their connecting pivots, react as a powerful compound toggle between the pins 38 and the presser-plate 14, and the latter is, therefore, 100 moved into proximity to the plate 3, with sufficient force to squeeze nearly dry a mop or similarly saturated fabric, which has been placed between said plates.

The pins 38 are eccentric to the axis of the shaft 11. By rotating said shaft the position of the pins 38, with 105 respect to the shaft 9, will be changed, and thus the stroke or movement of the presser-plate 14 will be lengthened or shortened, according as the pins 38 are in the position shown in Fig. 4, or that shown in Fig. 1. For turning the shaft 11, a lever 41 is provided, fixed 110 upon said shaft outside the frame 2. By springing the lever 41 outward, it may be turned to the desired posi-

tion, and then held in place by a stationary pin 43, which is adapted to enter any one of a number of holes 42 in said lever.

Movement of the lever 30 beyond a certain point is prevented by a stop or lug 35^a on the casing 39, which comes in contact with the under side of one link 36, when said lever is depressed to nearly a horizontal position.

What I claim is:—

- 10 1. A mop wringer comprising a frame having parallel side pieces provided with transverse slots, a stationary presser member fixedly secured between said side pieces, a movable presser member supported between said side pieces, an operating rock shaft turning in and movable along said slots and provided with oppositely disposed cranks, links pivotally connecting the cranks with the movable presser member and with a relatively fixed bearing respectively, and means for rocking said shaft.
- 20 2. A mop wringer comprising a frame having parallel side pieces provided with transverse slots, a stationary presser member fixedly secured between said side pieces, a movable presser member pivotally supported at its lower portion between said side pieces, an operating rock shaft turning in and movable along said slots and provided with oppositely disposed cranks, links pivotally connecting the cranks with the movable presser member and with a relatively fixed bearing respectively, means for adjusting said relatively fixed bearing to change the throw of the operating rock shaft and its links.
- 30 3. A mop wringer, comprising a frame having parallel side pieces, provided with transverse slots, a fixed presser member fixedly secured between said side pieces, a movable presser member pivotally supported at its lower end between said side pieces, a rotary adjusting shaft journaled in said side pieces at a distance from said presser member, an operating rock shaft rocking in and movable along said transverse slots in said side pieces, parallel with said adjusting rock shaft, and between it and said movable presser member, and having oppositely disposed cranks, a link connecting said movable presser member and one of said cranks, a second link connected at one end eccentrically to said rotary adjusting shaft and at its other end

to the opposite crank, means for imparting rotary adjustment to said last mentioned shaft, and means for rocking the operating shaft.

4. In a mop wringer, a frame comprising parallel side pieces having transverse slots, a stationary presser member held in fixed position between said parallel side pieces, a movable presser member pivotally supported at its lower end between said side pieces, a rotary adjusting shaft journaled in said side pieces at a distance from said presser members and provided with an eccentric pin, an operating rock shaft movable in the transverse slot in said side pieces, parallel with said rock shaft, and between it and said movable presser member, and having opposite disposed cranks, a link connecting said movable presser member and one of said cranks, a second link connected at one end to the eccentric pin on said rotary shaft and at its other end to the opposite crank, means for rocking the operating shaft, a lever for rotating the adjusting shaft, and means for locking said lever.

5. A mop wringer comprising a frame, a stationary presser member held in fixed position between side pieces; a movable presser member pivotally supported at its lower end between said side pieces; an upper, supplemental part carried by said movable presser member, and pivotally supported at its lower end; a yielding, spring support for the upper end of said supplemental part, adapted normally to thrust it forward; and means for compressing said movable presser member upon said stationary member.

6. A mop wringer comprising a frame, a stationary presser member held in fixed position between side pieces; a frame for a movable presser member, pivoted at its lower end between said side pieces; a movable presser member attached to said frame; a supplemental presser member pivoted in said frame above said movable presser member and having its lower edge so disposed with reference thereto as to limit the forward movement of said supplemental part; a yielding spring support for the upper end of said supplemental part, adapted normally to thrust it forward; and means for compressing said movable presser member upon said stationary member.
